UNITED STATES PATENT OFFICE.

LUTHER HANSON, OF HALIFAX, COUNTY OF YORK, ENGLAND.

TIME-CHECK RECEIVER.

SPECIFICATION forming part of Letters Patent No. 319,090, dated June 2, 1885.

Application filed September 5, 1884. (No model.) Patented in England February 14, 1884, No. 3,261; in France May 31, 1884, No. 162,498, and in Belgium June 5, 1884, No. 65,395.

To all whom it may concern:

Be it known that I, LUTHER HANSON, of 5
Bowling Dyke Dye-Works, Halifax, in the
county of York, England, have invented cer-
tain Improvements in Time-Check Registers,
of which the following is a specification.

This invention relates to apparatus for reg-
istering the time at which workmen deposit
their time-checks on entering or leaving a
factory.

This improved apparatus belongs to that
class of time-registers wherein a series of re-
ceptacles are employed each corresponding
to a different time of day, and a mechanism
controlled by clock-work directs the checks
15 into one receptacle after another successively,
according to the different times at which the
checks are deposited.

Prior to my invention such registering ap-
paratus have been constructed with a circular
20 series of receptacles arranged on a stationary
bed, with a rotary shaft above them carrying
a traveling spout, which terminates success-
ively over one after another of the recepta-
cles, and is moved from each to the next at
25 predetermined intervals of time by an escape-
ment controlled by clock-work.

My invention aims to dispense with the re-
volving spout and provide an improved and
30 simplified mechanism for controlling the op-
eration.

Figure 1 of the accompanying drawings is
a side elevation of the preferred form of my
invention, the inclosing-case being in section.
35 Fig. 2 is a plan of the working parts, the in-
closing-case being omitted. Fig. 3 is a side
elevation, and Fig. 4 a plan, of a modification;
and Fig. 5 is an elevation of another modifi-
cation.

40 A is the inclosing-case, in the side of which
is an opening for the dropping of the checks,
from which opening a short spout or chute, V,
extends downward. B is a circular table
mounted on a rotary shaft, D, which is stepped
45 in a bearing, E, at its lower end, and its upper
end has a bearing in a cross-piece, F.

Fixed on the shaft D is a barrel, G, on which
is wound a cord, H, which is carried over
sheaves I I I, and is attached at its end to a

weight, J. The tension due to this weight 50
thus imparts to the shaft D and table B a
normal tendency to revolve in one direction.

On the table B is placed a series of boxes or
receptacles, C C, to receive the checks, which
boxes are, by the intermittent rotation of the 55
table B, brought successively under the fixed
chute V in order to receive the checks dropped
through the chute. Each box corresponds to
a separate time of day, or, rather, to a separate
interval between two predetermined times. 60

In the upper part of the casing A is ar-
ranged a clock-work and part of the releas-
ing mechanism for effecting the intermittent
rotation of the table. This clock-work is in-
closed in a frame, K, Fig. 2, and on one of its 65
shafts—as, for instance, the shaft L—is fixed
a toothed cam-wheel, M. A lever, N, is hinged
at P, and its end rests in the teeth of this
wheel, and is lifted and dropped as the wheel
slowly turns in the direction of the arrow in 70
Fig. 1. A rod, R, is jointed to the lever N,
extends down, and is connected to a hammer-
arm, S, the free end a of which stands over
the end b of a lever, T, and to the opposite
end of this lever T a bolt or pin, U, is con- 75
nected. This bolt is adapted to enter any one
of a series of holes, c c, formed in the table B,
and while in either hole it acts to hold the
table from rotating. As seen in Fig. 2, there
is one hole c to each box C. The clock-work 80

is so timed that the wheel M drops the lever
N as often as the boxes C are desired to suc-
ceed one another under the chute V. As the
lever N is lifted it lifts the hammer-arm S, and
as it is dropped the arm S falls. Its end a strikes 85
the lever T and lifts the bolt U out of the hole
c, which it occupies. The table B, being then
no longer restrained, begins slowly to revolve.
Meanwhile the bolt U has fallen back and rests
on the surface of the table, and when the move- 90
ment of the table brings the next succeeding
hole c under it, it drops in and arrests the table.
In this operation one box has passed out from
under the chute V with whatever checks may
have been deposited in it, and the next suc- 95
ceeding box has taken its place under the chute.
With the proportions shown, where forty-eight
boxes C are provided and the releasing mech-

anism operates every five minutes, the machine will record the arrivals and departures for four hours without presenting any box twice beneath the chute. This gives an abundance of time for the clerk to take out the checks and make the necessary entries. For the convenience of the workmen, two opposite clock-faces, X and W, may be employed, the hands of which receive their motion from the shaft L through bevel-gears Z Z. In places where a larger number of work people are employed, the boxes C may be made larger and deep enough to hold any number of checks, as shown in Fig. 3, and when a larger number of workmen arrive or depart at one time than at other times, I arrange different-sized boxes accordingly, as illustrated in Fig. 4. In this figure the table is arranged to make one revolution in twelve hours, and the releasing mechanism is operated every five minutes; consequently the table is provided with one hundred and forty-four holes, c c, which are spaced, as shown, at different distances apart to suit the varied sizes of the boxes, and in order that during the intervals when no workmen are arriving or departing the table shall turn proportionally but a short distance. It is one of the important advantages of my releasing mechanism that it alone is capable of being adapted to such adjustment or proportioning of the apparatus.

In lieu of holes being formed in the table, notches may be cut in its edge, as shown at c c in Fig. 5. My improved apparatus provides a reliable and effective register with simple mechanism, and avoids the complications and liability to clogging which result from the use of a revolving spout or chute.

I am aware of the construction of time-check register disclosed in United States Patent No. 262,979, dated August 22, 1882.

I claim as my invention—

1. The combination, to form a time-check register, of the intermittently-rotating horizontal table B, mounted on a vertical axis, a circular series of boxes, C C, borne thereby, a stationary chute, V, under which said boxes pass successively, and a clock-work mechanism for controlling the intermittent advances of the table, all combined and arranged to operate substantially as set forth.

2. The combination of table B, means, substantially as described, for imparting to it a tendency to revolve in one direction, a series of holes or sockets, c c, in said table, a bolt or pin, U, adapted to enter said holes, mechanism, substantially as described, for withdrawing said bolt, and a clock-work adapted to control the operation of such mechanism, substantially as set forth.

3. The combination of table B, means, substantially as described, for imparting to it a tendency to revolve in one direction, holes c c in said table, bolt U, lever T, hammer-arm S, connecting-rod R, lever N, toothed wheel M, and a clock-work adapted to rotate said wheel, substantially as set forth.

In witness whereof I have hereunto signed my name in the presence of two subscribing witnesses.

LUTHER HANSON.
